UNITED STATES PATENT OFFICE

2,211,800

APPARATUS FOR RECLAIMING MATERIAL
SUCH AS POWDER OR FLOCK

Wayne B. Thompson, Winchester, Mass., assignor to Spray Engineering Company, Somerville, Mass., a corporation of Massachusetts

Application April 3, 1937, Serial No. 134,845

9 Claims. (Cl. 209—240)

The present invention relates to the reclaiming and cleaning of comminuted material such as powder or flock to render it fit for re-use after it has been sprayed or otherwise directed at an object, has not adhered thereto, and has become contaminated with impurities which would cause a finish to be dirty or otherwise defective.

In numerous flock applying operations flock of various kinds such as comminuted wool, silk, rayon, or cotton fibres, or the like or "cellophane" flock, mica flock, or the like, is discharged against an object having on its surface or surfaces a moist film of adhesive to which it is intended that the flock should adhere. As the flock is discharged it spreads out, some of the particles striking the object to be coated and a considerable portion of them not striking the object at all. For a given flock applying operation this flock which does not strike the object is, of course, wasted, but in addition, not even all the flock which strikes the object adheres to it. When the surface to be coated is substantially normal to the direction of flock discharge, a relatively large amount of flock that contacts the object adheres thereto, but when the surface is not substantially normal to the direction of flock discharge, a relatively large amount of the flock that contacts the object glances therefrom and mingles with the free particles of flock in the surrounding atmosphere. This last statement is true both when the flock strikes the adhesive coating and when the flock discharge is used to remove mounds in previously applied flock, as noted at page 3, left column, lines 3-8, of my Patent No. 2,064,505, December 15, 1936.

Since a great part of a given quantity of flock discharged at an object to be coated either does not strike the object or glances therefrom and since flocks of various kinds are relatively expensive, it is customary as a matter of economy to perform the applying operation either within a suitable booth or at the mouth of one, the excess material being collected in the booth for re-use or being conveyed therefrom to a remote point of collection. As a result of discharging flock within or into a booth, parts or surfaces thereof become covered with a layer of flock which adheres to foreign matter on these surfaces or gathers impurities from the air. This results in the production of lumps or heterogeneous masses which, if not removed before the flock is reapplied to an object, would cause the finish thereon to be uneven and lumpy.

It should be pointed out, however, that partly because of the very lightness of flock particles,

which renders them easily disturbed by air currents in their environment, and partly because as a practical matter flocking cannot be carried out under ideal conditions, it frequently happens that not all the excess flock is taken up by a booth. Some of the flock becomes scattered to the floor, surrounding walls, ceilings, beams, or other objects in the room, where it collects in considerable quantity. In gathering up such flock it is swept or brushed from the floor, etc. and as a result particles of foreign matter, broom, bristles, etc. become mixed with the flock, all of which obviously would serve to render impossible the production of a smooth and even flock finish on an object when this flock is re-applied to an object.

As those who use flock well know, even in its dry state it tends to ball up or to cling to what ever it contacts, but there is a further factor in flock application which augments this balling up and clinging tendency. In glancing from a moist, adhesive-coated surface, the scattered flock particles carry some of the adhesive with them, and as a consequence these particles become attached to other particles in the air with which they collide. The result is the production of lumps of flock the particles of which are adhesively bonded together. Inasmuch as these bonded lumps mingle with the remainder of the excess flock which is collected for re-use, it will be seen that these lumps assume the undesirable status of broom particles, bristles, or other foreign matter which must be removed before the flock is re-applied if the finish on the work is not to be uneven and lumpy, for these adhesive-bonded lumps are just as deleterious as are particles of any foreign matter to the production of a smooth and even flock finish.

It being desirable to save and re-use the flock which is in excess as the result of an applying operation, and as such used flock tends for various reasons to contain impurities or formations which cause the finish on the article being coated to be uneven and lumpy, it is the principal object of the present invention to provide an apparatus by which comminuted material such as flock or powder can be rid of foreign particles or lumps in an easy, rapid, and efficient manner. It is a further object of the present invention to provide an apparatus for this purpose such that large quantities of the contaminated material can be reclaimed and such that the reclaiming operation can be carried on continuously, additional quantities of material being introduced into the

apparatus as desired without requiring the stoppage of its operation.

To the accomplishment of these objects and such others as may hereinafter appear, the various features of the present invention reside in certain constructions, combinations, and arrangements of parts fully set forth hereinafter and then pointed out broadly and in detail in the appended claims, possessing advantages which will be readily apparent to those skilled in the art.

The various features of the present invention will be readily understood from inspection of the accompanying drawings, illustrating the best physical embodiment of the invention at present known to the inventor, in which:

Figure 1 is a view in front elevation of the re-claiming apparatus;

Fig. 2 is a view in left side elevation of the apparatus shown in Fig. 1;

Fig. 3 is a view in right side elevation of the apparatus shown in Fig. 1.

Fig. 4 is a view of the apparatus in plan, partially in section, taken along the line 4-4 of Fig. 3;

Fig. 5 is an enlarged detail view in front elevation from Fig. 1 showing the screen agitating means;

Fig. 6 is an enlarged detail view in left side elevation from Fig. 2, partially in section, showing the cam actuation of the screen agitation means; and

Fig. 7 is an enlarged detail view in plan of a portion of the screen agitating means.

The illustrated embodiment of the present invention is shown only for purposes of disclosure as embodied with the flock applying apparatus disclosed in my Patent No. 2,194,487, granted March 26, 1940. I wish to be distinctly understood as not meaning that the present invention is limited to such embodiment, for a reading of the following specification and claims will make it clear that said flock applying apparatus is here utilized only as one means for directing the material to be reclaimed to the remainder of the apparatus with which the present invention is primarily concerned. The present invention is here shown as embodied with said flock applying apparatus merely because of the resulting facility in disclosure and because the arrangement provides an increased utility for the flock applying apparatus.

Referring to the drawings, the illustrated embodiment of the present invention is provided with suitably braced upright frame members 41 (Figs. 1, 2, and 3) which support a container comprising an upper or entrance portion 42 open at its top and bottom and a lower or hopper portion 43 the top of which forms an open continuation of the bottom of the entrance portion 42. The front and rear walls 44 and 45, respectively, of the hopper 43 converge downwardly and merge in a rounded bottom 46 (Fig. 3) and the side walls 47 of the hopper are vertical. The front wall 48 of the entrance portion 42 is vertical throughout, while its rear wall 49 extends vertically from the hopper 46, then rearwardly and upwardly (Figs. 2 and 3) and then vertically again to terminate substantially at the level of the front wall 48.

The container comprising the entrance portion 42 and the hopper 43 receives the powder, flock, or other comminuted or finely divided material to be reclaimed, and since it is intended, as explained hereinafter, that the material be dis-

charged from an outlet at the bottom of the container into an entraining air current, means is provided for constantly stirring up and agitating the material in the container to insure its even and continuous passage to the rounded bottom 46. Experience has shown that when the outlet from a hopper into an entraining air current is at the bottom of the hopper, and therefore at the bottom of the quantity of the material to be let out, gravity alone cannot safely be relied upon to insure the continuous and even flow of finely divided matter from the outlet.

To insure that the hopper bottom is supplied with material in an even and continuous manner for the above-stated purpose, the hopper is provided with a series of six horizontal shafts 50 (Figs. 2 and 4) which are journaled in the side walls 47. This shaft construction is the same as that disclosed in my said Patent No. 2,194,487 and functions in the same way to support T-shaped agitators 51 for rotative movement, there being three agitators 51 on each shaft. By reason of this construction it will be seen that 18 agitators are provided extending throughout the hopper 43 generally and functioning, when the shafts 50 rotate, to thoroughly agitate and stir up the material in the hopper and cause it to descend to the bottom thereof without interruption.

It is preferred that the agitators 51 be rotated simultaneously and continuously, and for this purpose the right hand end of each shaft 50 outside the hopper is provided with a gear 52 fixed thereto and adapted to mesh with the links of an endless chain 53 (Fig. 3). A gear 54 (Fig. 3) journaled to the lower portion of the hopper also meshes with the links of the chain 53, the purpose of this gear 54 being explained hereinafter. One of the shafts 50 is provided on its left hand end with a pulley (not shown) fast thereon which is caused to rotate by means of a belt driven by an electric motor 55 (Figs. 1, 2, and 3), and by reason of this construction the gears 52 and 54 are caused to rotate simultaneously, resulting in the simultaneous rotation of the shafts 50 and the agitators 51. The gears 52 and 54 and the chain 53 are concealed by a safety cover 56 and the pulley and the belt may be provided with a safety cover 57.

The construction so far described is substantially the same as that disclosed in my said Patent No. 2,194,487 and provides power actuated agitators for maintaining the material in the hopper 43 in a stirred up condition so that as fast as material leaves the hopper from the outlet in its rounded bottom 46, as will be presently described, more material descends to take the place of that which has passed out the outlet.

In order to provide for the transfer of material from the hopper 43, the rounded bottom 46 thereof is, as more fully set forth in my said Patent No. 2,194,487 provided at the base of the front wall 44 with a horizontal slot 58 (Fig. 4) through which the material may pass from the hopper. In order to insure the positive transfer of material from the hopper into the slot 58 a rotatable brush construction is provided for driving and sweeping the material across and into the slot. This brush construction is the same as that shown in my said Patent No. 2,194,487, and for purposes of disclosure here may be said to be provided with a brush rod 60 (Fig. 4) operatively connected to the gear 54 above referred to, the brush rod 60 being provided with bristle clusters 61 (Fig. 4) of such length as to engage the rounded bottom 46 of the hopper 43 and the face 75

of the hopper wall 44 about the slot 58. With this arrangement the brush construction rotates with the agitators 51 and in addition to further agitating the material in the hopper 43 sweeps it across and into the slot 58.

It is intended that the material passing into the slot 58 be received by a horizontal tube or conduit portion 61 (Fig. 1) supported across the base of the front hopper wall 44 so as to cover the slot 58, and as is shown in detail in my said Patent No. 2,194,487, the portion of the tube 61 covering the slot 58 is provided with spaced horizontal slots which are aligned with the slot 58, so as to form passages into the tube 61 from the hopper 43.

In order that the material entering the tube 42 from the slot 58 be air-entrained in the tube and thus be discharged therefrom and from the apparatus, the central portion of the tube 61 opposite the portion thereof abutting the hopper wall 44 is provided with an opening 62 (Fig. 1), and intersectingly of the opening the tube 61 is provided with a circular transverse partition 63, as disclosed in my said Patent No. 2,194,487. The partition 63 thus divides the tube 61 and the opening 62 into two parts.

The opposite ends of the tube 42 form outlets and are suitably connected to the intake ends of suitable exhaust fans or blowers 64 and 65 of standard construction which may be connected to a source of power (not shown) such as electricity, and the discharge ends of the blowers are connected by nipples 66 and 67, respectively, to lengths of tubing 68 and 69, the free ends of which are provided with nozzles 70 and 71, respectively.

By reason of this construction, viewing Fig. 1, it will be seen that when the blower 64, for example, is in operation, a condition of unbalanced air pressure is established within the tube 61 between the portion of the opening 62 to the left of the partition 63 and the left hand end of the tube 61, the air entering the opening 62 from the atmosphere and moving in a current towards the left hand end of the tube. The entraining action of a current of air upon flock, powder, etc. in its path being well known, it will be apparent that any material that enters the left hand half of the tube 61 from the hopper 43 is entrained by the air current set up by the blower 64 and is drawn through the left hand part of the tube 61, the tubing 68, and its discharge nozzle 70. Precisely the same operation takes place with respect to the element associated with the tube 61 to the right of the partition 63, viewing Fig. 1, when the blower 65 is in operation.

In order to permit or to prevent the transfer of material into the tube 61 from the hopper bottom through the slot 58, the tube 61 is provided interiorly with a pair of sleeves which are fully disclosed in my said Patent No. 2,194,487 and are located one on each side of the partition 62 and are associated with the slots formed in the tube 61 in alignment with the hopper slot 58. The sleeves fit the tube 61 loosely enough to permit their sliding along the tube, but snugly enough so as to form with the slots therein effective valves for preventing, when desired, the flow of material into the tube while the blowers 64 and 65 are in operation.

In order to slide the sleeves in the tube 61, each is provided (Fig. 1) with a depending lug 72 which fits and extends through an associated longitudinal slot formed in the bottom of the tube 61. Each sleeve is moved by its own moving

means independently of the other, and these moving means are of corresponding construction. Referring to Fig. 1, each lug 72 is pivotally and slidably connected to the upper yoked end of a pivoted bell crank lever 73, while the other arm of the bell crank lever 73 is pivotally secured to the upper end of a link 74 the lower end of which is pivotally secured to one end of a lever 75. Through suitable shaft and lever connections herein shown in the drawings and fully described in my said Patent No. 2,194,487, the other end of each lever 75 is connected to a treadle lever 76 having a pedal 77, and with this construction when either pedal 77 is depressed the associated bell crank lever 73 moves the associated lug 72 and sleeve outwardly (Fig. 1) so that the hopper slot 58 and the associated slot in the tube 61 are uncovered.

In order to retract the pedals 77 from their depressed condition, that is, in order to maintain each pedal 77 normally elevated and therefore maintain the sleeves within the tube 61 normally in slot-covering position, coil springs 78 and 79 are provided to maintain each pedal 77 normally elevated and each bell crank lever 73 normally in the position shown in Fig. 1.

To summarize the operation of the structure described thus far, it will be appreciated that the container formed by the entrance portion 42 and the hopper 43 is first filled with the contaminated material which is to be reclaimed, this material extending substantially from the top to the bottom of the container and burying, as it were, the agitators 51 and the brush 59-60. No material passes into either half of the tube 61 since the slots therein are closed by the sleeves which are held in position by reason, ultimately, of the springs 78 and 79. The motor 35 is connected to electric current, causing the shafts 50, the agitators 51, and the brush 59-60 to rotate so that the mass of material in the hopper 43 is at once agitated and stirred by the agitators 51 and is further stirred and agitated by the brush 59-60.

The operator then connects the blower 64, for example, to electric current, thereby causing the blower to establish a condition of unbalanced air pressure between the portion of the opening 62 leading into the left half (Fig. 1) of the tube 61 on one hand and the associated end of the tube 61 on the other hand, or more comprehensively, on the nozzle 70 carried by the tubing 68.

The apparatus is thus in readiness to cause material to be withdrawn from the hopper 43 and be discharged from the nozzle 70 in order to be reclaimed. To achieve this discharge, the operator depresses the left hand pedal 77 whereupon the sleeve associated therewith is moved to the left, viewing Fig. 1, causing the passage between the hopper 43 and the left hand portion of the tube 61 to be uncovered with the result that the material in the hopper 43 is driven by the brush 59-60 through the passage and into the left half of the tube 61. As soon as the material enters the tube 61 it is entrained by the air current therein and is discharged from the nozzle 70 by the air issuing therefrom.

The above description of the operation of the apparatus applies to the discharge of material from the left half of the tube 61 and the nozzle 70, but in view of the structure that has been described it will be seen that this description of operation applies also to the discharge of material from the right half of the tube 61 and the nozzle 71.

In order to adapt the above described appara-

- tus for use in reclaiming contaminated material, the side walls of the container entrance portion 42 do not terminate upwardly at the level of the top of the front wall 43 thereof, as is the case in 5 the disclosure of my said Patent No. 2,194,487, but continue thereabove, as shown in Figs. 2 and 3, to form the side walls 90 of a chamber 81 provided with a top 82. The chamber 81 extends over the hopper 43 and the entrance portion 42, 10 from side to side and from front to back of the latter, and has an open front and an open back. It is contemplated that there be associated with 15 the chamber 81 suitable means for separating from the material to be reclaimed foreign matter that is in it. While the separating means may have any construction or mode of operation desirable for the purpose, it is preferred in the 20 illustrated embodiment of the present invention, that the separating means perform a screening function. To this end, at the back of the chamber 81, that is, above the uppermost vertical portion of the rear wall 49 of the container portion 42, each of the side walls 80 is provided interiorly 25 with vertical and slightly spaced angle irons 63 which by reason of their spacing form ways for receiving slidingly the frame sides 84 of a screen 85. As shown in Fig. 1, the screen 85 extends transversely across the chamber 81, completely filling the rear end of the passage therethrough, 30 and terminating downwardly slightly below and in front of the upper edge of the rear wall 49 of the container portion 42. The upper frame portion 86 of the screen 85 passes upwardly through a slot 87 (Fig. 6) in the top 82 so as to extend 35 above the apparatus. Adjacent the front edge of the slot 87 the top 82 is reinforced by an angle iron 88 (see Figs. 1, 5, 6, and 7), and adjacent the rear edge of the slot 87 the top is provided with a reinforcing strip 89.
- 40 The function of the screen 85 is to permit the passage therethrough of the material which it is desired to reclaim, while preventing the passage of adhesive-bonded particles, lumps, pieces of broom, bristles, etc., or other foreign matter. 45 To achieve this screening action the operator of the apparatus directs the discharge from the nozzles 70 and/or 71 against the screen 85, it having a mesh suitable for its intended purpose. Since the material to be screened is withdrawn 50 from the hopper 43 in the illustrated embodiment of the present invention, and since the screen 85 is located just in front of the uppermost portion of the rear wall 49, it will be apparent, as shown in Figs. 2 and 3, that any particles stopped 55 by the screen and not passing through it will fall back into the container portion 42 and the hopper 43.
- In order to collect for re-use the material 60 which passes through the screen 85 and which has had impurities and undesirable matter removed therefrom, the illustrated embodiment of the present invention contemplates the provision of a second chamber 90 located behind and forming a continuation of the chamber 81, and into 65 which the reclaimed or screened material passes. The chamber 90 has substantially the same height as the combined heights of the container portion 43 and the chamber 81, as shown in Figs. 2 and 3. Bounding the chamber 90 are a left 70 hand side wall 91, which may be integral with the side wall portion 80, a rear wall 92, a top 93, which may be a continuation of the top 82, and a right hand side wall comprising a lower panel 94 and an upper portion 95 forming an outlet duct leading to the inlet side of a motor driven 75

exhaust fan or blower 96 provided with a bag 97, the purpose of which will be described hereinafter. The chamber 90 is supported by rear frame members 98 and by front frame members 99 and 100, the member 99 being bent forwardly 5 and downwardly, and then downwardly, as shown in Fig. 2, so that for greater rigidity its lower end may be secured to a brace 101 extending between the front and rear frame members 41.

Completing the chamber 90 is a front wall 102 located behind the rear wall 49 of the container portion 43, and a floor comprising a tray 103 slidable on ways 104 (angle irons) mounted on the front wall 102 and the rear wall 92 in such position that the tray 103 is located adjacent the bottom of the side wall 91. To facilitate the sliding of the tray 103 on the ways 104, the front edge of the tray is provided with an upwardly bent lip 105, and the rear edge of the tray is reinforced against buckling by an angle iron 106 fixed to the under surface of the tray adjacent the rear edge.

With the above-described construction it will be seen that there is provided a chamber 90 into which screened material passes, the portion 25 of the chamber lying below the level of the screen 85 forming a container for holding any screened material dropping into it, and the slidable tray 103 affording means whereby the container may be emptied of material. In order to facilitate 30 the emptying of the container when the tray 103 is pulled out, the bottom edge of the panel 94, on the right hand side of the apparatus, is connected to a pan 107 (Figs. 1, 2, and 3) which extends downwardly and to the left, as indicated 35 in Fig. 1, and is flanked on its sides by front and rear walls 108 and 109, respectively, depending vertically from the chamber 90. With this construction the pan 107 and the walls 108 and 109 form a chute so that when the tray is pulled 40 on its ways 104, material dropping from the chamber 90 strikes the pan 107 and flows to its lower edge where it may be caught in a suitable receptacle (not shown).

Viewing Fig. 1, it will be seen that while the 45 screen 85 is an intersticed structure, permitting the passage therethrough of flock particles, yet by reason of the interstices being small enough to prevent the passage of lumps or undesirable foreign matter, the screen offers to a limited extent a resistance to the passage of the material 50 into the chamber 90. The blowers 64 and 65 are preferably relatively small, but even if they were large so as to create a relatively great air current, the passage resisting action of the screen 55 85 would still be present, and in view of the feltering tendency of material such as flocks made of animal or vegetable fibres, much of the material would cling to the screen and only a small amount would pass through under the impetus afforded by the air current from the blowers. To prevent this action, that is, to insure 60 that a maximum amount of material directed at the screen 85 passes therethrough, the present invention contemplates maintaining a strong, 65 material-entraining current of air through the screen 85 and the passage formed by the chambers 81 and 90. The present invention also contemplates for this same purpose, when necessary, the maintenance of the screen 85 in an agitated 70 condition while the material is being directed against it.

As the first means of achieving this end the blower 96 is provided, being mounted on a platform 110 supported by suitably braced front and 75

rear frame members 111 and 112, respectively, located rearwardly of the container portion 42 and the hopper 43 and to the right of the chamber 90, as will be seen by comparing Figs. 1 and 4. The blower 96 is of relatively large capacity so as to cause a strong current of air to enter the front of the chamber 81, pass through the screen 85, enter the chamber 90, and then leave it by way of the outlet 95. With this construction and mode of operation it will be seen that as soon as the material discharged from the nozzles 70 and/or 71 enters the chamber 81, the air current created by the blower 96 acts on the material in several ways. It first serves to 10 entrain and add impetus to the discharged material to cause it to strike the screen with relatively great force as compared to that which would be afforded by the current from the blowers 64 or 65 alone. Balls or lumps of flock 20 particles are in this manner broken up. Since the air current created by the blower 96 passes through the screen, this current also serves both to push and to pull through the screen interstices the material adjacent those interstices. Finally, 25 the current created by the blower 96 serves to entrain the screened material. As a consequence the air current from the blower 96 functions to facilitate the passage of material to and through the screen and to break up lump formations, and 30 acts to counteract the resistance which the screen offers to the passage of material therethrough.

By reason of the inherent feltering and balling up tendency of flocks such as those made of animal or vegetable fibres, even the air current 35 created by the blower 96 may be insufficient to cause a maximum amount of flock to pass through the screen. Stated in another way, it may be that particles or lumps of flock or foreign matter will collect on the screen and cover its interstices in spite of the action of the air current 40 created by the blower 96 to cause the particles of flock to pass through the screen. When this takes place the effective size of the screen becomes reduced, the particles matted together and clinging 45 to each other and to the screen serving to lower its efficiency. In order to prevent or minimize the tendency of particles or lumps to cling to the screen in opposition to the force of the air current for causing them to pass through 50 the screen, the illustrated embodiment of the present invention contemplates that any clinging material and foreign matter be constantly shaken from the screen.

To this end, viewing Figs. 1, 2, 3, 5, and 6, 55 there projects forwardly from the front face of the upper frame portion 86 of the screen 85 an arm 113 having a flat under face resting on the curved surface of a cam 114. This cam is secured to one end of a shaft 115 journaled in supports 60 116 secured to the horizontal web of the angle iron 88 at the right of the top 82, viewing Figs. 1 and 5, and the other end of the shaft 115 is provided with a sprocket 117. The teeth of this sprocket mesh with one bight of an endless chain 65 118, the opposite bight of which meshes with the teeth of a sprocket 119 journaled on one of the agitator shafts 50. The shaft 50 is extended outwardly to the right of the apparatus, viewing Fig. 1, so that the sprocket 119 clears the cover plate 56 and is aligned with the sprocket 117. In 70 order to steady the shaft 50, adjacent its sprocket end it is received in a bearing 120 supported on an arm 121 extending forwardly from the frame member 100 and in turn steadied by a brace 122.

Referring again particularly to Fig. 6, it will be

seen that the cam 114 is provided with a shoulder 123 connecting the opposite ends of the curved surface on which the arm 113 rests. With this construction, together with the sprocket and chain construction described above, it will be seen 5 that when the sprocket shaft 50 is rotated, i. e., when the motor 55 is in operation and the agitators 51 are rotating, the motion of the shaft 50 is transferred by the chain 118 to the sprocket 117, so that the shaft 115 and the cam 114 are 10 caused to rotate. Since the shoulder 123 on the cam provides that its curved surface is not circular or continuous, the rotation of the cam in engagement with the arm 113 causes the screen 85 to rise and fall repeatedly. Since the shoulder 15 123 is abrupt, it will also be seen that although the screen 85 rises because of the changing height of the rotating cam surface, the screen 85 falls by gravity as soon as the high point of the cam leaves the end of the arm 113. By making the 20 screen 85 of relatively heavy construction, or at least causing the frame thereof to be relatively heavy, it will be seen that the screen will fall with considerable jar. As a result, the jarring of the screen will shake loose the material collected on it and which has not passed through. Some of this material will fall back into the hopper 43, while some particles will be drawn through the interstices of the screen 85 thus cleared. In either event, the removal from the 25 screen in this manner of material collected on it maintains the effective area of the screen 85 at a maximum and therefore permits a maximum screening of material directed at the screen from without the entrance portion 42 and drawn towards the screen by the current of air set up by the blower 96.

The arm 113 is located centrally between the ends of the screen frame portion 86 so that the screen will rise vertically in its ways 83. It will 40 be apparent that in the cam and arm construction described above the fall of the screen will ordinarily be measured by the height of the shoulder 123 of the cam, and that upon the withdrawal of the high point of the cam from 45 the arm 113, the gravitational effect of the fall of the screen will cause the arm 113 to strike the cam, so that the arm would be the stop for limiting the fall of the screen. As this might cause too great a strain on the arm 113 and the cam, 50 it is preferred that the arm and the cam function only in the raising of the screen, and that its fall be limited by other means.

For this purpose the opposite ends of the rear face of the upper frame portion 86 of the screen 55 are provided with brackets 124 (Figs. 6 and 7) to which bolts 125 are secured vertically with their heads directed downwardly. Lock nuts 126 hold the bolts 125 in place and permit the vertical adjustment of the bolts, and the reinforcing strip 60 89 adjacent the rear edge of the slot 87 forms a striking surface for the bolt heads. With this construction the position of the bolts 125 can be adjusted so that their heads are spaced from the strip 89 a distance slightly less than the height 65 of the cam shoulder 123, thereby providing that when the high point of the cam 114 leaves the end of the arm 113, and the screen 85 falls, the heads of the bolts 125 strike the strip 89 to stop the fall of the screen, and the end of the arm 70 113 does not come down on the cam 114 or engage it during the fall of the screen. As a consequence, the fall of the screen imposes no strain on the arm 113, and no strain is imposed on the cam 114 for the same reason.

In the statement above that the screen construction should be relatively heavy so as to provide a jar in its fall sufficient to shake loose from the screen particles collected or matted on it, a screen of metallic construction was primarily in mind. In view of the fact that it may not always be possible to have a screen of such construction, or that in a different embodiment of the present invention a metallic screen would not be desirable, means may be provided for causing the screen to jar sufficiently, regardless of the weight of the materials of which it is made.

For this purpose, the outer ends of the brackets 124 which support the bolts 125 extend beyond the sides of the apparatus as indicated in Figs. 5 and 7, and are each provided with a depending eye 127 which receives one end of a depending coil spring 128, the opposite end of which is clipped to an upstanding eye 129 carried by a bracket 130, the right hand bracket (Fig. 3) being supported on the side wall 80 adjacent the duct 95, and the left hand bracket (Fig. 2) being supported on the side wall 80—91. With this construction, the upward movement of the screen 85 under the influence of the cam 114 places the springs 128 under tension so that when the high point of the cam leaves the arm 113, the springs 128 pull the screen 85 downward with considerable force, causing the bolts 125 in striking the strip 89 to impart a jar to the screen. It will be appreciated that the spring-return construction described in this paragraph may be dispensed with when the screen 85 has sufficient weight to cause gravity to impart thereto the necessary jar to shake from the screen the material clinging to it.

By reason of the construction described above it will be seen that a maximum amount of material passes through the screen 85 and is entrained in the chamber 90 by the air current created by the blower 96. But if the chamber 90 had only the structure that has been described for it thus far, it will also be seen that the air current created by the blower 96 would cause most of the screened or reclaimed material to pass out of the chamber 96 by way of the duct 95 and then into the blower 96 and its exhaust bag 97. Only a small amount would drop out of the air current. While this mode of operation would be possible with a suitable blower and bag arrangement, it will be apparent that it would, somewhat in the manner of a bag type vacuum cleaner, require that periodically the bag be removed from the blower, be emptied, and then be replaced, during all of which the apparatus would be out of commission. As the speed with which the tray 103 can be pulled out and then in again on its ways 104, is very great as compared to the time required to remove, empty, and replace the bag 97, it is desirable that means be provided for causing as much as possible of the entrained screened material to drop out of the air current in the chamber 90 and into the container portion thereof, not passing out the outlet duct 95 and to the bag 97 at all.

To this end it is contemplated that the chamber 90 be provided with an impingement device which the entrained material strikes upon being screened and is caused by the impingement to drop out of the air current. While the impingement device may take any one of a variety of forms or constructions, it is preferred in the illustrated embodiment of the present invention to provide a combined baffle and impingement surface 131 (Figs. 1, 2, 3, and 4) lying in the path of flow 75 of the greater portion of the entrained screened

material. The baffle 131 comprises a vertical curved sheet having a height substantially that of the chamber 90 as indicated in Fig. 1, and is secured (Fig. 4) at its right hand edge portion to the adjacent side of the outlet duct 95. The upper edge of the baffle 131 terminates adjacent the chamber top 93 and is secured there by a bracket 132. The baffle extends rearwardly and to the left of the chamber 90, with its rear vertical edge lying about midway between the front and rear of the chamber 90 and spaced sufficiently from the side wall 91 of the chamber to provide ample room for the passage of air between it and the wall 91.

With this construction it will be seen that the path of flow of the greater portion of the entrained screened material is obstructed by the baffle 131 so that the material screened is caused to impinge on the baffle. The result of this impingement is that most of the entrained material drops out of the air current, dropping from the baffle 131 into the container portion of the chamber 90 bottomed by the tray 103. By causing the baffle 131 to extend across the greater portion of the passage through the chambers 81 and 90, only a relatively small portion of the entrained material passes beyond the baffle and into the blower 96 and its bag 97. As a consequence, the apparatus may be used for a considerable period before it is necessary to empty the bag of the entrained material collected in it, a period that is much longer than would be the case were means not provided for causing the bulk of the material entrained in the air current to drop from it before reaching the chamber outlet duct 95.

The mesh of the screen 85 being suitable for its intended purpose, it will be seen that foreign matter which it is desired to separate from the material does not pass through the screen, but is stopped thereby, dropping back into the hopper 43. Likewise, any material the lumps of which have been broken up by impingement with the screen 85 either passes through the screen or is shaken off and drops back into the hopper 43. This material is further agitated and stirred up in the hopper, eventually finding its way to the bottom thereof, where it is swept by the brush 59—60 into the tube 61 and is eventually re-discharged against the screen 85. While this mode of operation provides that foreign matter may be discharged against the screen a plurality of times, it will be apparent that this foreign matter always falls back into the hopper, while the material to be reclaimed that did not pass through the screen on the first discharge, for example, eventually does so on the next or later discharges. With a given quantity of contaminated material initially in the container portion 42 and the hopper 43, the natural result of a continued discharge of the material against the screen, involving a plurality of discharges for some portions of the material, would be the presence in the container of the chamber 90 and in the bag 97 of all the material capable of being screened, and a residue in the hopper 43 of the undesirable material which it is desired to separate out. It will be apparent, however, that since foreign matter does not pass through the screen 85, the container portion 42 and the hopper 43 can be kept continually full of material without interrupting the operation of the apparatus and without causing foreign matter in the first filling to be eventually screened into the chamber 90. When it is desired to remove the foreign matter from the hopper 43, it is necessary merely to remove a panel (not shown) covering

an opening in the rear wall of the hopper 43, upon doing which the contents of the hopper will flow down the chute 135 (Figs. 1 and 3).

It is believed that in view of the above descriptions of the various elements of the apparatus, little more need be said to explain its use for reclaiming contaminated material. It will be noted that since the sprocket 119 is secured to an agitator shaft 50, the screen 85 begins to rise and fall whenever the motor 55 is turned on to rotate the agitators 51. As a consequence, the screen 85 is in a state of movement before the operator depresses a pedal 71 to cause the discharge of contaminated flock from a nozzle 70 or 71, and this movement continues after he has removed his foot from the pedal 71. In this manner provision is made that the material discharged from the nozzles 70 and 71 strikes a screen that is always in motion so that at all times during the use of the apparatus, no opportunity is afforded for particles or lumps of material or foreign matter to cling to the screen and cut down its effective screening area. The blower 96 may have its own actuating connection or may be connected to the circuit of the motor 55. In either event, the blower 96 is thrown into operation before the operator depresses a pedal 71, so that a current of air is caused to flow through the passage formed by the chambers 81 and 90 and out the outlet 95 before contaminated material is discharged against the screen 85. As a result, this air current serves to facilitate the passage of material to and through the screen by reason of the entraining, pushing, and pulling effect of the current, and the current cooperates with the agitation of the screen by causing material shaken loose therefrom or broken up to pass into the chamber 90. Once in the chamber 90 the bulk of the entrained screened material strikes the baffle 131 and drops to the container bottomed by the tray 103. Any material not dropping to the container but remaining entrained in the air current passes out the outlet 95 to the bag 97 where it is saved and not wasted. As a result, the container in the chamber 90 and the bag 97 together insure that all the screened material is collected for re-use. In re-using the reclaimed material, it may be replaced in the hopper 43 and discharged through the nozzles 70 and/or 71 at some surface to be coated. It will be understood, however, that instead of being replaced in the hopper 43, the reclaimed material may be placed in the containers used with any suitable or well known applying apparatus.

Nothing herein explained is to be interpreted as limiting the various features of the present invention in the scope of its application to use in connection with the particular apparatus or the particular mode of operation or both selected for purposes of illustration and explanation. While the particulars of construction herein set forth are well suited to one mechanical form of the invention, to the use to which it is put, and to the method of reclaiming disclosed, it is not limited thereto nor to the disclosed details of construction nor to the conjoint use of all disclosed features. It is not to be understood that these particulars are essential since they may be modified within the skill of the artisan without departing from the true scope of the actual invention, characteristic features of which are set forth in the following claims by the intentional use of generic terms and expressions inclusive of various modifications.

What is claimed as new is:

1. An apparatus for reclaiming material such as powder or flock having, in combination, a container for the material to be reclaimed, a screening device for separating from the material foreign matter commingled therewith, and means operable for withdrawing the commingled material and foreign matter from the container and projecting them against the screening device, said screening device being so positioned with respect to the container that foreign matter and also material not passing through the screening device drop therefrom back into the container for re-withdrawal and projecting. 5

2. An apparatus for reclaiming material such as powder or flock, having, in combination, a container for the material to be reclaimed, a screening device for separating from the material foreign matter commingled therewith, and fluid current means operable for withdrawing the commingled material and foreign matter 10 from the container and projecting them against the screening device, said screening device being so positioned with respect to the container that foreign matter and also material not passing through the screening device drop therefrom back into the container for re-withdrawal and projecting. 15

3. An apparatus for reclaiming material such as powder or flock having, in combination, a container for the material to be reclaimed, a screening device for separating from the material foreign matter commingled therewith, means operable for withdrawing the commingled material and foreign matter from the container and projecting them against the screening device, 20 and means for moving the screening device to prevent the accumulation of material and foreign matter thereat, said screening device being so positioned with respect to the container that foreign matter and also material not passing through the screening device may drop therefrom back into the container for re-withdrawal and projecting. 25

4. An apparatus for reclaiming material such as powder or flock having, in combination, a container for the material to be reclaimed, a screening device for separating from the material foreign matter commingled therewith, means operable for withdrawing the commingled material and foreign matter from the container and projecting them against the screening device, and means for creating an air current through the screening device to facilitate the action of the screening device on the material projected against it and for carrying away from the screening device material that passes therethrough, said screening device being so located with respect to the container that foreign matter and also material not passing through the screening device may drop therefrom back into the container for re-withdrawal and projecting. 30 40

5. An apparatus for reclaiming material such as powder or flock having, in combination, a container for the material to be reclaimed, a screening device for separating from the material foreign matter commingled therewith, means operable for withdrawing the commingled material and foreign matter from the container and projecting them against the screening device, means for moving the screening device to prevent the accumulation of commingled material and foreign matter thereat, and means for creating an air current through the screening device to facilitate the action of the screening device on the material projected against it and 35 45 50 55 60 65 70 75

- for carrying away from the screening device material that passes therethrough, said screening device being so located with respect to the container that foreign matter and also material 5 not passing through the screening device may drop therefrom back into the container for withdrawal and projecting.
6. In an apparatus for reclaiming material such as powder or flock, the combination with a 10 passage-providing construction, a screen located in the passage for separating from the material foreign matter commingled therewith, and means for creating a current of air in the passage through substantially the entire area of the 15 screen, of means, including a conduit portion provided with a nozzle, operable for the projection against the screen of a discharge of air-entrained commingled material and foreign matter, the area of the discharge end of the nozzle 20 being relatively small as compared to the area of the screen, and the nozzle and conduit portion being so constructed that the discharge from the nozzle can be played about over the screen area.
- 25 7. In an apparatus for reclaiming material such as powder or flock, the combination with a passage-providing construction, an agitatable screen located in the passage for separating from the material foreign matter commingled therewith, 30 with, means for agitating the screen, and means for creating a current of air in the passage through substantially the entire area of the screen, of means, including a conduit portion provided with a nozzle, operable for the projection 35 against the screen of a discharge of air-entrained commingled material and foreign matter, the area of the discharge end of the nozzle being relatively small as compared to the area of the screen, and the nozzle and conduit portion being so constructed that the discharge from the nozzle 40 can manually and at will be successively projected against different screen area portions.
8. In an apparatus for reclaiming material

such as powder or flock, the combination with a passage-providing construction, a screening device located in the passage for separating from the material foreign matter commingled therewith, air current creating means, including a manually supportable and movable conduit portion provided with a discharge nozzle so that the discharge from the nozzle can be played about over the area of the screening device, operable for projecting the commingled material and 10 foreign matter in an unconfined condition against the screening device, and means separate from the first air current creating means for creating a current of air through the screening device and the passage-providing construction 15 to facilitate the action of the screening device on the material projected against it and to carry away from the screening device the material passing therethrough, of means for collecting 20 said screened material.

9. In an apparatus for reclaiming material such as powder or flock, the combination with a passage-providing construction, a screening device located in the passage for separating from the material foreign matter commingled therewith, air current creating means, including a manually supportable and movable conduit portion provided with a discharge nozzle so that the discharge from the nozzle can be played about over the area of the screening device, operable for projecting the commingled material and foreign matter in an unconfined condition against the screening device, and means separate from the first air current creating means for creating a current of air through the screening device and the passage-providing construction to 25 facilitate the action of the screening device on the material projected against it and to carry away from the screening device the material passing therethrough, of means for causing 30 screened material to drop out of the air current 35 so that it may be collected for re-use.

WAYNE B. THOMPSON.
